UNITED STATES PATENT OFFICE.

JOSEPH H. SARIS, OF BELOIT, WISCONSIN.

CORK-INSERT MACHINE.

1,406,689.

Specification of Letters Patent. Patented Feb. 14, 1922.

Application filed July 18, 1919. Serial No. 311,891.

To all whom it may concern:

Be it known that I, JOSEPH H. SARIS, a citizen of the United States, residing at Beloit, in the county of Rock and State of Wisconsin, have invented certain new and useful Improvements in Cork-Insert Machines, of which the following is a specification.

This invention pertains in general to the manufacture of transmission or brake linings of the character described in my Patent No. 1,184,701, dated May 23, 1916. These lining strips made of woven fabric and treated to render them more durable, are 10 perforated at intervals, and cork disks are inserted into the holes. The cork inserts project slightly from the face of the lining and serve to initially engage the brake drum or clutch member, as the case may be, so 15 as to cushion the gripping action of the band. The disks are forcibly pressed into the holes, and thus effectually retained therein.

The primary object of the present invention is to provide mechanism of an automatic character for inserting cork disks into the holes of a perforated lining strip in a most economical manner and to such a degree of accuracy and uniformity as to produce a commercial article possessing qualities serving exceptionally well the purposes for which these linings are used.

Because of the characteristics of the small cork disks and the alacrity and precision 25 with which they must be handled in order to operate the mechanism at the desired speed, considerable difficulty is encountered; and one of the objects of my invention is the provision of novel mechanism for feeding in 30 a very effectual manner the cork disks from a hopper to a mechanism which presses the disks into the perforations of the lining.

As a further object, my invention contemplates, generally stated, the provision of 45 novel devices and mechanisms operated automatically in predetermined timed relation for placing a perforated lining strip accurately in position to receive the cork disks, feeding the corks from a hopper and delivering them into co-operative relation to the strip, and pressing the corks into the holes of the perforated strip. The co-operating instrumentalities by which these 50 general operations are effected and the

finished strips discharged from the machine 55 will be more particularly described hereinafter.

Other objects and attendant advantages pertaining to the construction and functions of the devices disclosed herein, and to 60 the relative relation and co-operation of parts, will be appreciated as the invention becomes better understood by reference to the following description when considered in connection with the accompanying drawings, in which—

Figure 1 is a side elevation of a machine embodying my improvements, looking at the strip intake side;

Fig. 2, an elevation of the opposite side 70 of the machine;

Fig. 3, a front elevation of the machine;

Fig. 4, a plan sectional view taken substantially on line 4—4 of Fig. 3;

Fig. 5, a vertical sectional view, longitudinally through the machine, taken substantially on the line 5—5 of Fig. 4;

Fig. 5^a, a fragmentary sectional view taken substantially on the line 5^a—5^a of Fig. 4;

Fig. 6, a sectional view taken substantially on the line 6—6 of Fig. 5;

Figs. 7, 8 and 9, vertical cross-sectional views taken on the line 7—7, 8—8 and 9—9, respectively of Fig. 4;

Fig. 10, enlarged detail sectional view taken on the line 10—10 of Fig. 6, showing the disk picker and centering head elevated; and

Fig. 11, a similar sectional view with the 90 disks pressed into the holes in the lining strip by the head.

Before entering into a detailed description of the mechanism I will give a brief account of the operation, substantially in the 95 order of the functions performed. At the proper time in the operation, a perforated lining strip is rapidly fed lengthwise onto a bed to a position wherein holes in the strip overlie a corresponding number of retractable or depressible abutments in the bed. A head above the bed carries a row of centering members and in lateral alignment therewith, a row of cork disk pickers. At this stage of the operation the head is elevated with the centering members in vertical alignment with said abutments in the bed. A continuously operating feed mecha-

2

nism carries the corks from a hopper to a position beneath each picker. The cross head will now be depressed, causing its centering members to enter the holes in a lining strip and accurately center such holes, that is, correct the position of the strip, and cause the pickers to engage the row of corks therebeneath so that upon return or upward movement of the head, said row of corks will be lifted thereby. As soon as the strip has been centered or accurately positioned on the bed, a clamping means will be actuated to rigidly clamp the strip in such position. The head will now be shifted horizontally to bring the pickers into vertical alignment with the holes in the strip and will then be moved in a vertical direction to forcibly press the corks into the tapered holes. The abutments beneath such holes are held stationary during this movement and constitute a rigid bottom against which the corks are pressed by the head and thus limited as to the depth to which they may be inserted. The head will now withdraw, leaving the cork disks firmly inserted and secured in the lining strip, and the clamping means will release such strip, whereupon the latter will be rapidly discharged lengthwise of the bed. A new strip immediately follows the filled strip, and the operation is repeated seriatim. The several operations just described are automatically effected in predetermined timed relation, so that it is only necessary for the attendant to see that the lining strips are properly fed to the machine. It should be noted, however, that aside from the general operation just described, my invention contemplates a novel means and method of delivering the cork disks from a hopper to the inserting mechanism and delivering the corks in such order and relative relation to the holes in the perforated strip as to enable insertion of the corks in an exceptionally simple and effective manner and quickly, considering the number of the corks inserted. It should also be understood that the particular mechanism disclosed is shown simply for the purpose of illustrating the principles of my invention, and the construction and arrangement of mechanism to the ends desired might be considerably modified without departing from the spirit and scope of the invention.

55 Referring to Figs. 1 to 4 inclusive it will be observed that the frame work of my present machine consists of a base 15 supported by suitable legs and carrying a pair of rigid upright standards 16 and 17. Interposed between and rigidly mounted on the ledges 18 of these standards is a horizontal bed designated generally by character 19. Upon this bed both the lining strips and cork disks are delivered, the strips being fed lengthwise onto the bed from the right hand end

viewing Fig. 3, and the corks being fed laterally onto the bed from the left hand side, viewing Fig. 5. A driving shaft 21 journaled in bearings at the top of the standards operates the several operable devices with the exception of the strip-discharging rollers which are driven from an independent pulley 22, as will be described later. These standards 16 and 17 have rearwardly extending vertical side walls 23 and 24 respectively defining the sides of a cork disk hopper or magazine designated generally by character 25. Interposed between these walls is a disk feeding mechanism which will now be described.

80 The cork disks are dumped promiscuously into the hopper 25 as shown in Figs. 4 and 5, which has a stationary bottom 26 and a front wall 27, the latter of which is supported to reciprocate horizontally on the ways 28 carried by the side walls 23 and 24. The bottom of the hopper between the parts 26 and 27 is open and traversed by a plurality of endless aprons or belt carriers, designated generally by 29, trained over drums 30 and 32. It will be noted that the drum 32 is disposed in close proximity to the bed 19 and that the upper reaches of the aprons are disposed substantially in the horizontal plane of the top of said bed. The upper reaches travel over a platform 33 supported by the side walls 23 and 24, and the aprons are spaced apart by stationary guides 34 which extend substantially from end to end of the upper reaches and carry means 35 which will be presently described, defining the sides of the respective carrier ways. The purpose of these aprons is to deliver the cork disks from the hopper 23 onto the bed 19 in juxtaposition to the cork inserting mechanism. Other feed mechanism is employed, however, in co-operation with the aprons for thus delivering the corks, since the aprons alone are ineffectual for this purpose. The aprons are driven from the cylinder 31, 110 the shaft 35 of which is adjustable as shown in Fig. 2, to take up slack, and equipped as shown in Fig. 1, with a sprocket wheel 36. This sprocket wheel is driven continuously while the machine is in operation and any suitable driving means may be employed. In this case, the sprocket wheel has a chain connection with the wheel 37 (Fig. 4), this wheel having a one-way ratchet driving connection with the cam shaft 38, suitably journaled on the side walls of the machine and equipped as shown in Fig. 2, with a sprocket gear 39 having chain connection with the driving shaft 21. The driving shaft in turn is driven by a belt pulley 41 through the agency of a suitable clutch 42 which in this instance is adapted to be thrown into and out of engagement by means of a hand lever 43 (Fig. 3). The wheel 44 fixed to the shaft 21 is used simply for turning the shaft by 120

115

120

125

130

hand when it is desired to operate the machine slowly for inspection or for any other purpose. It will thus be seen that when the clutch 42 is engaged the aprons 29 will be continuously revolved in a clockwise direction, viewing Fig. 5.

With the mechanism so far described, the cork disks in the hopper 25 resting on the belts 29 will be carried thereby beneath the horizontal ledge 45 of an agitating member of which the wall 27 is a part. This member 45 forms the top wall for the carrier ways, the sides of which are defined by the upstanding partitions 46 (Figs. 4 and 8). The horizontal reciprocating action of the part 45 agitates the corks in the hopper and causes them to assume a flat position and to enter upon the aprons between the partitions 46 and thus be carried along thereby. In practice, the corks are manually stirred in the hopper 25 to evenly distribute them over the several aprons and to arrange them flat thereon. It is desired to maintain a full row of corks on each apron and to positively advance these rows toward the bed 19 to insure the proper feeding of the corks thereto. In order to insure such positive feed, I have provided several feeding elements operable upon the top of the corks for urging them against the aprons to obtain greater frictional contact therewith and also for positively advancing them in the direction of the apron travel. Inasmuch as the corks are very light in weight and have a relatively high co-efficient of friction, they are extremely difficult to handle by mechanical means, but it will be seen that by urging the corks slightly against the leather aprons they will be advanced thereby whenever they are free to move forwardly. That is, at some intervals in the operation the rows of corks are held against advancing, due to the fact that the first corks in the rows are in set position waiting to be removed by the pickers or cork inserting means. During this idle period the aprons simply slip beneath these corks which have been fully advanced in the rows, but the belts are continually functioning in moving new corks into the ways or channels and in closing up any gaps between the corks. The corks are held against rising from the aprons by top plates or guides 47, shown in Figs. 4, 5 and 7. In the latter figure, it will be noted that the plates 47 are spaced sufficiently apart to enable feeder fingers 48 to operate between the plates and engage the top of the corks in a movement designed to positively feed the corks onto the bed 19. These feeder fingers 48 are attached to a feed head 49 as shown clearly in Figs. 5 and 7, which head is given a four-motion feed movement by mechanism which will be presently described. That is, the head 49, as shown in Fig. 5, is elevated. Its supporting and actuating mechanism

will lower the head until the feed fingers 48 rest upon and frictionally engage the cork disks in the several rows, whereupon the head will be fed forwardly toward the bed 19, then raised and returned again to the starting position. The head 49 is slidably mounted adjacent to its ends on horizontally disposed guide rods 51 pivotally supported at their rear ends at 52 so that the head 49 is free to rise and fall about the pivots 52, 75 but is constantly urged downwardly by the springs 50, Fig. 5^a, operating on the guide rods 51. The feed head supporting rods 51 are lifted against said spring pressure by means of cams 53 (Figs. 5^a and 7) fixed to the shaft 38 and operable upon upstanding arms 54 attached to the rods 51. Thus, when the shaft 38 is revolved the head 49 will be alternately raised and lowered. Means is now provided for reciprocating the head 49 horizontally on the guide rods 51. This movement is obtained from the cork-inserting head, designated generally by character 55, the construction and operation of which will be explained more fully hereinafter. 90 For the present, it will only be necessary to assume that the head 55 is reciprocated horizontally at predetermined intervals, and it might also be mentioned that it is reciprocated vertically. Links 56 pivotally connected at 57 to the head 55 rest and are slidably guided at their rear ends on the shaft 38 by reason of the slot engagement 58 therewith, as shown in Fig. 5, and are connected by forwardly extending links 59 to the head 49. Connection is also established between the feed head 49 and the member 45 through the agency of links 61 connected at their forward ends to the links 59 and at their rear ends to said members 45. It follows, therefore, that when the cork insert head 55 is reciprocated horizontally the feed head 49 and the member 45 will be likewise reciprocated horizontally, although the head 49 is given an additional movement in a vertical direction by the eccentric cam 53 for the purpose of bringing the feed fingers 48 into and out of engagement with the cork disks. 105

Viewing Figs. 5 and 10, it will be seen that the top 62 of the bed 19 is flush with the top of the aprons and that the bed extends into such close proximity to the aprons as to enable the corks to move freely onto the bed. In order, however, to prevent the corks from striking the edge of the bed as they are moved thereonto, I have equipped the bed with projecting spurs or guides 63, best shown in Fig. 10, which extend into the central peripheral grooves 64 in the aprons and enter beneath the corks so as to provide inclined guides causing the corks to ride freely onto the bed, or rather the ledge 65, which is simply an extension of the bed. The bed is shaped to provide semi-circular sockets 66 (Figs. 4 and 10) in alignment 110

with the rows of corks, and it will be manifest that the advancement of each row is limited by contact of the first cork therein against the end wall of its respective socket.

5 A traveling guard 67 overlying the corks intermediate the sockets 66 and the guide plates 47 serves to hold the corks down on the bed and properly guide them into the sockets 66, or rather to their final position 10 on the bed. This guard 67 is carried by and moves in synchronism with the feed head 49, and consequently will advance with the rows of corks. Viewing Fig. 10, it will be seen that the guard 67 overlies the first 15 two corks as they are advanced in each row so that when the row is moved forward these corks will be properly guided forward on the bed. The forward movement of the guard 67 is, however, shorter than that of the head 49, and to this end a lost motion 20 is required between these feeding members. To this end the guide-feeder 67 is supported by arched parts 68 fixed to rods 69, which are slideable in stationary guides 71 fixed to 25 the respective guide plates 47 upon which they are positioned. Expansion springs 72 on the rods 69 between the brackets 71 and the arches 68 serve to hold the latter against the head 49 so that the guard 67 will move 30 forwardly with said head. This forward movement of the guard 67 is, however, limited by the pins 73 on the rods 69 abutting against the brackets 71 at a point about midway of the forward movement of the 35 head 49. In other words, the guard 67 has a forward movement about one-half that of the feed head 49. The guard 67 simply rests on the corks and is advanced and retracted without moving vertically. Still another 40 auxiliary feed device is employed for feeding the corks ahead, consisting of a rotary pusher 74 above each row at the rear of the feed head 49 and fixed to a shaft 75, which is continuously revolved in a counterclockwise direction, viewing Fig. 5, by reason of 45 its chain connection 76 with a sprocket wheel 77 on the shaft 38, it being noted, (Fig. 1) that reverse gearing is employed to revolve the shaft 75 in the proper direction.

50 From the foregoing, it will be manifest that I have provided mechanism for positively feeding cork disks from a hopper to a set position from which the corks are removed by the inserting mechanism which 55 will be described hereinafter. Attention is directed to the fact that it is necessary to deliver at relatively short intervals, a relatively large number (21 in actual practice) of cork disks to a set position, and that these 60 corks must be moved positively and with precision to such position. This is necessary because a picker and an insert device is used to lift the series of corks from the set position and insert them into the holes 65 in the perforated lining strip. The feed

operation will be retracted to more clearly illustrate the co-operative action of the several agencies employed to feed the disks in the manner desired. It will be recalled that the aprons 29 travel continuously and have 70 the effect of constantly urging and carrying the corks forwardly in the rows to close any gaps therein.

Since the corks are very light and have a tendency to stop upon the slightest contact 75 or pressure against the side guides, the several auxiliary feed devices operate intermittently upon the tops of the corks for pressing them into greater frictional contact with the aprons and for positively moving 80 them forwardly. Thus during the operation, the reciprocating head 45 agitates the corks in the hopper and serves in part to spread them flatly on the aprons and also serves as a guide permitting but a single 85 layer of corks to enter upon each apron. This head 45 is reciprocated in unison with the feed head 49 and the feeder-guard 67 by reason of the mechanism described above. The rotary pushers 74 press the corks against 90 the aprons if any should stop at this point, and thus cause the corks to be positively moved forward. The function of said members 48 and 67 will be obvious from the description given above. They are brought 95 into action immediately after the first corks in the rows have been removed, and serve to positively move the next succeeding corks in the rows forwardly to the extent desired.

Coming now to the cork-inserting mechanism, reference will be had more particularly to Figs. 3, 5, 6 and 10, which best illustrate the construction. It will be observed that the head 55 referred to above is constructed on its underside to carry a plurality of tapered centering pins 78 and laterally offset therefrom and in alignment therewith, a series of picker and insert lugs 79 each equipped on its underside with spurs 81. The head 55 is supported at opposite 100 ends upon horizontal ways 82 on the plungers 83 which are guided in suitable bearings 84 on the standards 16 and 17 to reciprocate vertically thereon. These plungers are reciprocated by eccentrics 85 (Fig. 115 2) fixed to the driving shaft 21 so that upon each revolution of this shaft the head 55 will be lowered and raised. During the periods that the head is elevated, it will be shifted horizontally on the ways 82 to alternately position the centering pins 78 and the pickers 79 in vertical alignment with the abutments 86 which are slideable vertically in the openings 87 in the bed 19. To effect this movement a pair of cams 88 fixed 110 to the shaft 38 and springs 89, are employed. The springs operable between the plunger-connected parts 91 and the head 55, as shown in Fig. 4, continuously urge the head rearwardly on the ways 82 to a position limited 120 125 130

by contact of the head-connected parts 92 against the cams 88. It will thus be manifest, viewing Figs. 5, 10 and 11, assuming that a lining strip has been positioned on the bed 19, that the first downward stroke of the plunger 83 with the head in the position shown in Fig. 5, will cause the fingers 78 to enter the holes in the perforated lining strip 93, thereby correcting the position of the strip so that its holes are co-axial with the holes 87 in the bed. At the same time the spurs 81 will be driven into the corks positioned in the respective sockets 66, and upon raising the head the corks thus engaged will be lifted. During this movement and immediately following the centering of the strip it will be clamped securely in position on the bed and held therein by a clamping plate 94. At the initial elevating movement of the head 55 from the position shown in Fig. 5, an ejector stem or follower 95 underlying each cork in the set position will be given an upward movement to raise its respective cork from its socket 66, thus preventing displacement of the corks from the spurs 81, as might be occasioned by the corks rubbing against the side walls of said sockets. The mechanism for operating the ejector pins will also be described later. Fig. 10 shows the head 55 elevated at the rear of its first working stroke, and thereupon the cam 88 will shift the head horizontally to its foremost position in which the pickers 79 are in vertical alignment with the holes of the lining strip. By this shifting movement the head 55 will actuate the feed elements 48 and 67, causing new disks to be positioned in the sockets 66 described above. Upon the next succeeding depression of the head 55, the cork disks carried thereby will be forcibly pressed into the tapered holes in the lining strip in the manner shown in Fig. 11, the abutments being held rigidly in the position shown to limit the extent of insertion of the corks. In this regard, it will be noted that the abutments permit protrusion of the corks slightly beyond the bottom face of the lining strip. The projecting cork faces have a distinctive function as described in my patent mentioned above. At the rear of the second working stroke, the cam 88 will allow the spring 89 to return the head 55 to its rearmost or starting position. During this latter movement, the clamp 94 will release the lining strip which will be discharged lengthwise from the bed 19 by mechanism described hereinafter. A new strip will be immediately fed onto the bed by the feeding device, which will be described later.

The clamping plate 94 rigidly attached to four sets of rods 96 slidable through the bed, as shown in Figs. 3 and 10, is constantly urged downwardly into clamping position 65 by expansion springs 97 operable between

the underside of the bed 19 and the cross heads 98 on the rods. The clamping pressure is released by the action of arms 99 which are oscillated at the proper times for raising the cross heads 98 to relieve and restore the effect of the springs 96 on the clamping plate. The arms 99 are fixed to a rock shaft 101 which extends to the outer side of the standard 17 and is equipped therewith as shown in Fig. 2, with a manually operable lever 102 carrying a roller 103 adapted to be actuated by the cam 104 which is fixed to the cam shaft 38. This cam 104 is so shaped that it will, by actuating the arms 99, cause the clamping plate 94 to clamp a lining strip to the bed as soon as the strip has been centered or its position corrected on the bed, and will hold the strip so clamped until after the corks have been inserted, whereupon the clamping plate will be raised permitting the strip to be discharged, and a new strip to be fed in.

The ejector pins 95 are carried by a head 105 connected by means of the parts 106 to a rock shaft 107, which extends beyond the side 90 of the standard 16, as shown in Fig. 1, and has connected thereto a link 108, adapted to be operated by a cam 109 fixed to the cam shaft 38. It will be manifest that the cam 109 is shaped to momentarily actuate the ejector pins 95 at the proper time for the purpose described above.

Referring back to the cork-inserting stroke of the head 55 and to Figs. 5 and 11, it will be recalled that the abutments 86 are to be held stationary during the cork-inserting stroke and are to be freely retractable during the centering stroke. To this end, the abutments are carried by a head 111 slidable upon rods 112 and constantly urged upwardly by the expansion springs 113 on the rods. Pivoted locking members 114 are adapted to be swung into and out of locking engagement with the head 111 and for this purpose said members are attached to a rock shaft 115 having a connection 116 with the rock shaft 101. During the period of operation shown in Fig. 5, the locking members 114 are disposed out of engagement with the head 111 and the latter will be elevated under the influence of the springs 112 when the centering pins are withdrawn. During movement of the shaft 101 in a clockwise direction to clamp the lining strip on the bed, the connection 116 will be actuated permitting the contractile springs 110 to move the members 114 into locking engagement with the head 111 and thus support the latter in a stationary position until the completion of the cork-inserting operation at which time the locking members 114 will be withdrawn from the head 111 simultaneously with the release of the lining strip.

The mechanism for feeding the lining strips onto the bed and discharging them

therefrom will now be described. A feed table 117 supported by the standard 16 and shaped to receive the lining strip in line with the top of the bed 19, has mounted thereon a reciprocable carrier 118 carrying a pivoted feed dog 119 which projects through a slot 121 in the table and is adapted to engage in a hole of a lining strip positioned upon the table for the purpose of feeding this strip lengthwise thereon into engagement with the feed rolls 122 and 123. These feed rolls are revolved at a high speed and will deliver the strip rapidly onto the bed to a position limited by the stop 124 (Fig. 6), which as shown in Figs. 2 and 4, is pivoted at 125 and adapted to be raised from a stopping position by the cam 120 on the cam shaft 38, the spring 120' serving to lower the stop. The feed rolls connected by the spur gears are revolved by any suitable means, such for example as the worm 125 and gear 127, the latter of which is driven by a chain 128 from the driving shaft 21. The lower forward end of the dog 119, at the end of its forward stroke drops into a slot 129 in the table 117, so as not to interfere with the strip as it is fed into the machine by the roll, and upon retracting the dog carrier by means of the lever 131, the free end of the dog will ride up the incline at the end of the slot and be held in operative position to engage a new lining strip and move it forwardly upon the next actuation of the lever. This lever operated in synchronism with the discharging mechanism at the opposite end of the machine, is connected to such mechanism by the slide rod 132.

The discharging mechanism consists, primarily, of a pair of grippers 133 pivotally mounted at 134 on a carriage 135 slidable horizontally on a suitable frame extension 136, best shown in Figs. 2, 3, 4 and 6. The carriage 135 is reciprocated by a lever 137 connected to the rod 132, and it follows that the grippers 133 and the feed dog 119 will be reciprocated in unison. The gripper carriage 135 is moved in one direction by a cam 138, (Fig. 2) fixed to the cam shaft 38. The connection between these parts consists of a cam follower 139 which by its vertical movement oscillates a rock shaft 141 by means of an arm 142, and said shaft through the agency of the arm 143 and link 144 reciprocates the gripper carriage 135 in a direction to discharge the lining strip. An expansion spring 145 on the lever 132 (Fig. 6) returns the feed and discharge mechanism parts to normal position, as allowed by the cam 138. It will be observed that the grippers 133 have pointed ends 146 which will be positioned over the ends 147 of the strip when the grippers are advanced, the stop 124 having been previously raised above the path of the grippers. When the head 55 is depressed in the cork-inserting stroke, a presser bar

148 carried by the head will press the pointed ends 146 into the lining strip. When now the grippers are pulled forward they will draw the lining strip lengthwise off the bed and intermediate a pair of delivery rolls 149 and 151. These rolls are revolved at a high speed and will discharge the lining strip from the machine in a very rapid movement. The grippers 146 will be withdrawn from the lining strip by contact of their inclined opposite ends against the stationary stop 152 as soon as the strip has entered between the delivery rolls. These rolls are revolved in the present case by an independent drive pulley 22 mentioned above, through the agency of bevel gears 153 and spur gears 154.

While the machine as illustrated in Fig. 4, includes mechanism for inserting only 10 corks into a lining strip having a similar 85 number of perforations, it should be understood that in actual practice a lining strip of the particular character in mind as produced for commercial purposes, has about 21 holes and the machine is constructed to 90 insert a like number of corks. The number, however, is purely relative and is mentioned simply to illustrate that a considerable number of corks are handled and inserted automatically.

The machine runs at such speed as to discharge about 20 strips a minute. Since the operation of the machine is entirely automatic in character as has been fully described above, it will be manifest that 95 lining strips are filled with cork inserts very quickly and economically, and at the same time with a high degree of precision and uniformity. It will be noted that the light cork disks which are hard to handle are 100 positively controlled by the novel feed mechanism and placed in co-operative relation to the insert mechanism which forcibly presses the corks into the lining strip in such manner that the corks are very securely 105 retained therein. It will be further noted that the mechanism for attaining these ends is very simple, considering the working to 110 be performed and speed of operation. In conclusion, it is believed that the foregoing 115 conveys a clear understanding of the principles and objects of my invention, and while I have illustrated and described but a single working embodiment thereof, it should be understood that various changes might be 120 made in the construction and arrangement without departing from the spirit and scope of the invention as expressed in the appended claims: in which—

I claim:

1. In a machine for inserting cork disks into the holes of a perforated lining strip, mechanism for positioning a strip and a row of cork disks in juxtaposition on a bed, and means for lifting the row of corks, 130

- carrying them into vertical alignment with the holes in the strip, and pressing them into said holes.
2. In a machine for inserting cork disks into the holes of a perforated lining strip, mechanism for positioning a strip and a row of cork disks in juxtaposition on a bed, and a cork inserter head equipped with means for centering or correcting the position of the lining strip and with other means for lifting a row of corks and carrying them into inserting position. 75
3. In a cork inserter machine of the character described, the combination of a bed adapted to support a perforated lining strip, a hopper adapted to carry a quantity of cork disks, mechanism for removing the corks from the hopper and feeding them in rows corresponding in number and relation to the holes in the strip, into co-operative relation to said strip on the bed, and means for pressing the first corks of said rows into the holes in the strip. 80
4. In a cork inserter machine of the character described, the combination of a bed adapted to support a perforated lining strip, a hopper adapted to carry a quantity of cork disks, mechanism for removing the corks from the hopper and so delivering them onto the bed as to position a single cork alongside each hole in the strip, and means for lifting all the corks so positioned and pressing them in one operation into said holes. 85
5. In a machine for inserting cork disks into the holes of a perforated lining strip, the combination of means for supporting a perforated strip, a plurality of rows of corks, said rows corresponding in number and relative relation to the number and position of the holes in the strip, means for moving said rows of corks toward the strip, and means pressing the first cork in each row into its respective hole in the strip. 90
6. In a machine for inserting cork disks into the holes of a perforated lining strip, means for moving a series of corks from a set position and pressing them into the holes in the strip, means for feeding the corks toward said set position, and a connection between the cork inserting means and feeding means for actuating the latter by the former. 95
7. A machine for inserting cork disks into the holes of a perforated lining strip, a bed having a series of retractable abutments and adapted to support a perforated lining strip with the holes therein positioned over said abutments, means movable down through the holes in the strip for aligning them with the abutments, the abutments being retractable during such operation, means supporting the abutments rigidly in elevated position, and means for forcibly pressing cork disks into the holes and against said abutments when they are secured in said elevated position. 100
8. In a machine of the character described, the combination of a bed adapted to support a perforated strip, a head mounted above the bed to reciprocate in a vertical and a horizontal plane and equipped with means for lifting a series of disks corresponding in number and relation to the holes in said perforated strip, means for shifting the head horizontally to bring the disk lifting means into and out of alignment with the holes in the strip, and means for moving the head vertically to pick up a series of disks when out of alignment with said holes and press the disks into the holes when in alignment therewith. 105
9. In a cork insert machine, the combination of a bed adapted to carry a perforated lining strip, an endless apron for each hole in the lining strip and adapted to carry a row of cork disks toward the strip in lateral alignment with its respective hole, and means for removing the first cork in each of the rows and inserting such corks into the holes of the strip. 110
10. In a cork insert machine, the combination of means for supporting a perforated lining strip positioned to receive cork disks, a plurality of endless aprons, one for each hole in the strip and adapted to carry a row of cork disks toward the strip, and means for removing a cork disk from each row and inserting these corks in one operation into the holes of the strip. 115
11. In a cork insert machine, the combination of means for supporting a perforated lining strip, a plurality of continuously moving endless aprons, one for each hole in the strip for carrying a row of cork disks toward the strip, means for urging the corks against the aprons and for moving them forwardly therewith, and means for removing a single cork from each row and for inserting these corks in one operation into the holes in the strip. 120
12. In a cork insert machine of the character described, a head equipped with centering fingers and picker spurs, and mechanism for operating the head to center or correct the position of a perforated lining strip and to pick up a row of cork disks and insert them into the holes in the strip. 125
13. In a cork insert machine of the character described, a head equipped with centering fingers and picker spurs, mechanism for operating the head to center or correct the position of a perforated lining strip and to pick up a row of cork disks from a set position and insert them into the holes in the strip, and feed mechanism actuated by movement of the head to advance the corks to said set position. 130
14. In a cork insert machine of the character described, a head equipped with centering fingers and picker spurs, mechanism for operating the head to center or correct the position of a perforated lining strip and to 135

- pick up a row of cork disks from a set position and insert them into the holes in the strip, and disk feeding mechanism actuated by movement of the head for advancing the disks toward said set position.
15. In a cork insert machine of the character described, the combination of a bed, mechanism for feeding a lining strip lengthwise onto the bed, a stop in the path of the strip for limiting its advance, means for correcting the position of the strip to center its holes, means for inserting disks into said holes, and mechanism for discharging the strip from the bed at the completion of the cork inserting operation.
16. In a cork insert machine of the character described, the combination of a bed, mechanism for feeding a lining strip lengthwise onto the bed, a stop in the path of the strip for limiting its advance, means for correcting the position of the strip to center its holes, means for clamping the strip in such corrected position and releasing the strip after a cork-inserting operation, means for inserting disks into said holes, and mechanism for discharging the strip from the bed at the completion of the cork-inserting operation.
17. In a cork insert machine of the character described, the combination of a bed adapted to support a perforated lining strip and having a semi-circular socket in lateral alignment with each hole in the strip, a hopper adapted to carry a quantity of cork disks, mechanism for removing the corks from the hopper and delivering them into said sockets, and means for removing the corks from said sockets and pressing them into the holes in the strip.
18. In a machine for inserting cork disks or the like into the holes in a lining strip, the combination of a hopper for holding a quantity of disks, a series of laterally spaced endless aprons having their upper reaches in parallelism and moving through the bottom of the hopper, means defining ways along the sides of each apron, means for feeding the disks forwardly in the direction of travel of the upper reaches of the aprons to keep the disks in abutting relation, means for stopping the first disk in each row at a position in lateral alignment with a hole in which the respective disk is to be inserted, means for supporting a strip in proximity to said disks, and means for moving said first disks in their predetermined relative relation and inserting them into the holes in the strip.
19. In a machine of the character described, the combination of a series of endless aprons continuously driven and each supporting on its upper reach a row of cork disks, a stationary platform onto which each row of corks delivers, means for engaging the top of the corks and moving them in the direction of travel of the upper reach of said belt for keeping the corks in abutting relation, means stopping advancement of the rows, whereby to position the first cork in each row in predetermined relation to the hole in which the cork is to be inserted, means for supporting a perforated lining strip in co-operative relation to the first corks in said rows, and means for pressing said first corks into the holes in the strip.
20. In a machine for inserting cork disks into the perforations of a lining strip, the combination of means for supporting a strip in a cork-receiving position, means for feeding a series of corks corresponding in number to the holes in the strip, from a hopper to a position in the same relative relation as said holes in the strip, and means for moving said corks in unison from said position and pressing them into the holes in the strip.
21. In a machine for inserting cork disks into the perforations of a lining strip, a head having members for centering the holes in the strip and having other members for lifting cork disks from a given position and subsequently pressing them into the holes in the strip.
22. In a machine for inserting cork disks into the perforations of a lining strip, a head having members for centering the holes in the strip and having other members for lifting cork disks from a given position and subsequently pressing them into the holes in the strip, and means for moving said head to simultaneously center said holes and operatively engage a series of corks for subsequently lifting the latter.
23. In a machine for inserting cork disks into a series of holes in a lining strip, the combination of means for holding the strip in a stationary position, means for feeding a series of cork disks to a position alongside of the strip and in lateral alignment with the holes therein, and means for lifting said series of disks, moving them over and into axial alignment with the holes in the strip and pressing them into the holes.
24. In a machine for inserting cork disks into a series of holes in a lining strip, the combination of means for holding the strip in a stationary position, means for feeding a series of cork disks to a position alongside of the strip in the plane thereof and in lateral alignment with the holes, and means for lifting said series of disks, moving them over the holes and pressing them thereinto.
25. In a machine for inserting cork disks into the holes in a perforated lining strip, the combination of a bed for supporting the strip, retractable abutments in the bed coaxial with the holes in the strip, a head equipped with a series of centering members adapted to enter said holes in a centering action, whereupon said abutments will be retracted, means on the head for carrying a

series of cork disks in lateral alignment with said centering members, and means for alternately moving said centering members and disk carrying means into axial alignment with the holes, and for depressing the head, whereby to alternately center the holes and press the cork disks thereinto.

26. In a machine of the character described, the combination of a bed having a series of vertical openings and adapted to support a perforated lining strip the holes of which are co-axial with said openings in the bed, means for positioning the series of disks alongside the strip, a head equipped with a series of centering members and combined disk pickers and presses, and means for reciprocating the head in a vertical and a horizontal plane, whereby during one vertical reciprocation of the head said members will center the holes in the strips and the pickers will enter a series of disks, and whereby upon horizontal movement the pickers will be positioned over the holes in the strip and upon the next vertical reciprocation of the head the disks will be pressed into the holes in the strip.

27. In a machine for inserting a series of disks into the holes of a perforated lining strip, the combination of a series of continuously moving endless carriers each for moving a row of disks toward the strip, whereby the first disk in each row will be positioned alongside of the strip in lateral alignment with one of the holes therein, and means for lifting at one time all the disks next adjacent to the strip and pressing them into the holes therein.

28. In a machine for inserting disks into holes of a perforated lining strip, the combination of a bed for supporting a perforated strip, an endless carrier for each hole in the strip and disposed in a plane transverse to the longitudinal axis of the strip and in alignment with its respective hole, means for continuously moving said carriers so that each will move a row of disks toward the strip, means for limiting the position of the first disk in each row so that such disks are in the same relative relation as the holes in the strip, and means for moving the disks from such position and pressing them into the holes in the strip.

29. In a machine for inserting cork disks

into the holes of a perforated lining strip, the combination of a bed adapted to support a perforated strip, a hopper containing a quantity of cork disks, means for automatically delivering the corks from the hopper and arranging a plurality of such disks corresponding in number to the number of holes in the strip in a position corresponding to the relative relation of said holes, and means for removing said plurality of disks from said position and pressing them into the holes in the strip.

30. In a machine for inserting cork disks into the holes of a perforated lining strip, the combination of means for supporting a perforated strip and a plurality of corks in juxtaposition, a head equipped with cork pickers, and means for moving the head to pick up said plurality of corks, carry them into axial alignment with the holes in the strip and press them into said holes.

31. In a machine for inserting cork disks into the holes of a perforated lining strip, means for supporting a perforated strip, and a head having hole-centering members and disk-picker members and movable to alternately center the holes and press the corks previously picked up, into the holes.

32. In a machine for inserting cork disks into the holes of a perforated lining strip, the combination of means for supporting a strip in a stationary position, continuously moving carriers for feeding rows of corks toward the strip, said rows corresponding in number and relative position to the number and position of the holes in the strip, and means for pressing the first cork in each row into the corresponding hole in the strip.

33. In a machine for inserting cork disks into the holes of a perforated lining strip, the combination of means for supporting a perforated strip, a plurality of rows of corks, said rows corresponding in number and relative relation to the number and position of the holes in the strip, means for moving said rows of corks toward the strip, a head carrying means for centering the holes in the strip and other means for lifting the first corks in said rows, and means for operating said head to center the holes in the strip, lift said first corks and press them into the strips.

J. H. SARIS.
